UNITED STATES PATENT OFFICE.

ADAM J. BAUER, OF OWEGO, NEW YORK.

ADJUSTABLE WINDOW-SCREEN.

1,120,361.

Specification of Letters Patent.

Patented Dec. 8, 1914.

Application filed November 25, 1913. Serial No. 802,968.

To all whom it may concern:

Be it known that I, ADAM J. BAUER, a citizen of the United States, residing at Owego, in the county of Tioga, State of New York, have invented certain new and useful Improvements in Adjustable Window-Screens; and I do hereby declare the following to be a full, clear, and exact description of the invention, such as will enable others skilled in the art to which it appertains to make and use the same.

This invention relates to window screens and has for an object to provide a window screen that may be adjusted to fit any size of window and may be then locked in such adjusted position so that it will always be adjusted to that window.

A further object of the invention is to provide an extremely simple and inexpensive window screen that will be formed of a few parts that will not easily get out of order.

With the above objects in view the invention consists of certain novel details of construction and combination of parts hereinafter fully described and claimed, it being understood that various modifications may be made in the minor details of construction within the scope of the appended claims.

In the accompanying drawing illustrating this invention:—Figure 1 is a front elevation of the screen. Fig. 2 is a longitudinal sectional view through the window screen, on the line 2—2 Fig. 1. Fig. 3 is a cross sectional view through the window screen on the line 3—3 Fig. 1. Fig. 4 is a rear elevation of the screen showing the same in position for adjustment to a window prior to being locked in such adjusted position, with the nuts shown in dotted position to lock the screen in adjusted position.

Referring now to the drawing in which like characters of reference designate similar parts, the screen is shown to comprise a pair of oblong frames 10 and 11 placed end to end and joined together at their confronting ends by a pair of spaced tension devices 12. Each frame is equipped on the outer end bar with a friction element 12' of rough material.

Each tension device comprises a bolt 13 which passes through the confronting end bars 14 and 15 of both frames and is equipped between the bars with a helical

spring 16 or other spring that will serve to urge the frames apart. The head 17 of the bolt bears against the inner face of the end bar 14 of one frame and the nut 18 of the bolt is tightened up against the inner face 60 of the end bar 15 of the other frame.

The frame 11 is equipped on the top rail and the bottom rail with respective channel-iron guide extensions 19 and 20 which slidably receive the corresponding rails of the frame 10 and are each formed of a single sheet of metal bent upon itself to produce a double angle iron structure as shown, this construction serving to firmly hold the screen elements about to be described in 70 place.

A screen element 21 is stretched over the frame 10, and a similar screen element 22 is stretched over the frame 11, these elements being held firmly in place by the channel-iron extensions 19 and 20. Both channel-iron extensions are connected by a single upright metal bar 23 which serves to hold the extensions in rigid spaced relation so that binding of the frames will be positively 80 prevented during their relative movement toward and away from each other. It will be noted that the screen elements are substantially in continuation with each other so that the screen presents a substantially flat 85 surface on one side from end to end.

In applying the screen, the inner bars of both frames are forced together and the screen then inserted in the window, the bars then being released whereby the springs 90 force the frames apart so that the outer bars of the frames snugly engage with the window casing. As shown in Fig. 4 the nuts of the bolts may now be tightened up against the inner face of the related frame end bar 95 whereby both frames will be locked in this adjusted position so that the screen will always fit this particular window. After the screen has been adjusted to a window it can be easily removed or replaced by pressing 100 the frames 10 and 11 together against the pressure of the springs 16.

From the above description it will be seen that I have provided an extremely simple and inexpensive screen that may be adjusted to windows of various sizes and may be locked in any adjusted position, and further that the screen is formed of a few strong and durable parts that will not easily get 105 out of order.

What is claimed, is:—

1. An extensible screen including a frame, said frame including a transverse bar, guide members carried by the frame, and extending beyond the transverse bar, a fabric stretched over the frame and extending beyond the transverse bar, a second frame engaged slidably in the guide members, and having a transverse bar lying between the 5 guide members, a fabric stretched over the second frame, and tensioning devices engaged between the two transverse bars to hold them yieldably against movement toward each other.
- 10 2. An extensible screen including a frame, said frame including a transverse bar, guide members carried by the frame, and extending beyond the transverse bar, a fabric stretched over the frame and extending beyond the transverse bar, a second frame engaged slidably in the guide members, and having a fabric stretched over the second frame, tensioning devices engaged between the two transverse bars to hold them yieldably against movement toward each other, and means for limiting the movement of the transverse bars away from each other.
- 15 3. An extensible screen including a frame, said frame including a transverse bar, guide members carried by the frame, and extending beyond the transverse bar, a fabric stretched over the frame and extending beyond the transverse bar, a second frame engaged slidably in the guide members, and having a fabric stretched over the second frame, tensioning devices engaged between the two transverse bars to hold them yieldably against movement toward each other, and means for limiting the movement of the transverse bars away from each other.
- 20 4. An extensible screen including a pair of frames, a fabric element stretched over each frame, guide members carried by one frame slidably receiving the other frame, and tension devices connecting both frames, each tension device including a bolt passed through the confronting end bars of both frames, a helical spring on the bolt between said bars serving normally to urge said frames apart, the head of said bolt bearing against the inner face of one of said bars, and a nut on said bolt bearing against the inner face of the other of said bars, said nut being positionable at various points on the end of said bolt to limit expansion of said spring and hold said frames anchored at a predetermined relative position.
- 25 5. In testimony whereof, I affix my signature, in the presence of two witnesses.
- 30 6. ADAM J. BAUER.
